UNITED STATES PATENT OFFICE.

JACKSON FLECKENSTEIN, OF IONIA, MICHIGAN; ADELAIDE FLECKENSTEIN, GUARDIAN OF SAID JACKSON FLECKENSTEIN, A MINOR, ASSIGNOR TO FLECKENSTEIN VISIBLE GASOMETER COMPANY, OF CHICAGO, ILLINOIS, A CORPORATION OF DELAWARE.

MEASURING AND DISPENSING APPARATUS.

1,367,366.

Specification of Letters Patent.

Patented Feb. 1, 1921.

Application filed August 13, 1917. Serial No. 185,906.

To all whom it may concern:

Be it known that I, JACKSON FLECKENSTEIN, a citizen of the United States, residing at Ionia, in the county of Ionia and 5 State of Michigan, have invented certain new and useful Improvements in Measuring and Dispensing Apparatus; and I do hereby declare the following to be a full, clear, and exact description of the invention, such 10 as will enable others skilled in the art to which it appertains to make and use the same.

The present invention relates to measuring and dispensing apparatus, and has more 15 particular reference to a device adapted to measure and deliver predetermined quantities of gasolene and the like.

An object is to provide a device of this character with improved means for opening 20 and closing the inlet and discharge valves and admitting of the easy manipulation of the valves from a point below the containers of the device; to provide an improved connection between the containers of the device 25 for facilitating the discharge of the liquid from the container which is open to the discharge; and to provide an improved air inlet valve for venting the containers to offset the formation of a vacuum therein.

30 The invention also aims at the provision of means for sealing the air inlet valve to prevent access thereto after the same has been adjusted, and to prevent the introduction of liquid into the container through the 35 valve opening.

Other and more detailed objects will hereinafter in part become apparent and in part be stated in the following further disclosure of the invention, which invention comprises certain novel constructions, combinations 40 and arrangements of parts as will subsequently be rendered clear and later specifically pointed out in the claim.

In the accompanying drawings,—

45 Figure 1 is a front elevation of a measuring and dispensing device constructed according to the present invention.

Fig. 2 is a top plan view of the same.

50 Fig. 3 is a fragmentary enlarged vertical section through the air inlet valve and the parts surrounding the same.

Fig. 4 is a horizontal section taken

through the valve immediately above the sealing plate.

Fig. 5 is a detail perspective view of the 55 valve housing.

Fig. 6 is a fragmentary enlarged section taken vertically through the upper end of the adjacent containers, and showing the air pipe connection between the same. 60

Fig. 7 is a side elevation of the lower end of the device, showing the handle connection for operating the inlet and discharge valves.

Referring to these drawings, wherein like 65 parts are referred to by similar numerals of reference throughout the several views, 10 and 11 designate a pair of containers which may be inclosed in protecting jackets 12 formed of wire meshing or the like. The 70 containers 10 and 11 are provided at opposite ends with heads 13 and 14, the former being arranged against the lower ends of the containers and having connection with branches 15 of a discharge pipe 16. A valve 75 17, of preferably the rotary type is interposed in the discharge pipe 16 at its point of juncture with the branches 15 and is adapted to open the branches one at a time to the discharge pipe. 80

The upper heads 14 are connected to the branches 18 of an inlet pipe 19, and a valve 20, preferably of the rotary type is interposed in the inlet pipe 19 at its juncture with the branches 18 for communicating the 85 latter one at a time with the inlet pipe. The valves 17 and 20 are provided with operating arms 21 which are arranged at one end of the valves and extend substantially in the same direction. A rod 22 is pivotally 90 connected at its opposite ends to the outer extremities of the arms 21 to effect the simultaneous shifting of the valves. The ports of the valves 17 and 20 are arranged to open one of the containers to the inlet 95 pipe 19 while the opposite container is open to the discharge pipe 16. The lower valve 17 is provided on its opposite end with an operating handle 23 which projects downwardly from the valve and is arranged in 100 position for easy access to operate the valves.

As shown in Fig. 6, the upper ends of the containers 10 and 11 are in communication with one another by means of a pipe 24

which is substantially U-shaped and connected at its opposite ends to the heads 14 of the containers. The pipe 24 is an air pipe and is adapted to transfer air from one container while being filled into the opposite container for facilitating the discharge of the contents thereof. Should the inflow of liquid to one container be more rapid than the outflow from the opposite container, the 10 air compressed in the first container by the inflow of liquid thereto is conveyed through the pipe 24 into the container open to the discharge and forces the liquid therefrom under considerable pressure.

15 For the purpose of venting the containers at their upper ends and preventing the formation of a vacuum therein, each head 14 is provided with an air valve 25. The valve 25 is in the form of a disk, of metal 20 or the like, having upon its upper face a covering of cork 26, or other resilient material adapted to engage a valve seat 27 in the form of a shoulder which is ground in the lower face of the head 14. The disk 25 valve 25 is secured upon the lower end of a valve stem 28, which latter is in the form of a rod screw-threaded at opposite ends and carrying a pair of lock nuts 29 binding against the opposite sides of the valve 25 30 to hold it to the stem. The stem 28 passes upwardly through a bearing 30 comprising a part of the head 14 and has a spring 31 surrounding the rod and engaging at one end against the bearing 30 and at its opposite end against the pair of adjusting nuts 32 secured in locked relation and upon the upper end of the rod or stem 28. The spring 31 normally lifts the rod 28 and holds the valve 25 to its seat. The head 14 40 is suitably drilled or stamped at the opposite sides of the bearing 30 to form openings or passages 33 through the head which are normally closed by the valve 25.

This valve may be provided with a housing or protector 34 in the form of an enclosing casing adapted to fit over the head 14 and cover the openings 33. The housing 34 is adapted to prevent accumulation of dust, water, and the like, upon the upper 45 surface of the valve 25, and to prevent access to the spring 31 and the adjusting nuts 32 therefor. The protector 34 has an opening 35 in its upper end through which the stem 28 may project, and the protector is also 50 provided with a base or retaining flange 36 which projects from opposite sides of the casing 34 and is adapted to engage beneath the adjacent edge portions of a sealing plate which is detachably fitted over the adjacent 55 head 14. The plate 37 may be provided with recesses 38 in its under side to receive

the ends of the flange 36 for holding the latter in predetermined relation over the air valve and for preventing the sliding of the housing 34. The sealing plate 37 is provided with a substantially radially extending slot 39 in its forward edge to receive therethrough the inlet branch 18 and the valve housing 34. The plate 37 also has at its inner side, and toward its rear edge portion, an outwardly flaring slot 39 through which the air pipe 24 is adapted to project. The slot 39 is flared to admit the swinging of the plate 37 into position and for removing the same. A slotted lug 40 is formed upon 75 preferably the rear edge of the plate 37 for sealing the same in position when adjusted.

The arm 21 of the discharge valve is preferably offset forwardly at its free end to dispose the lower end of the connecting rod 22 in vertical register with its upper end. The stem 28 of the air valve projects upwardly through the housing 34 so that the thumb or finger may be pressed against the top of the stem to move the latter 85 downwardly against the tension of the spring 31 and open the valve 25 when desired.

The housing 34 is preferably provided with an enlarged head on its upper end 90 forming an exterior annular shoulder which faces downwardly, and which is suitably apertured to admit air to the valve when open. This head prevents rain, dust and other accumulations from passing to the 95 interior of the casing 34 and thus protects the valve and prevents foreign substances from entering the containers.

What is claimed is:

In a measuring and dispensing apparatus, the combination of a pair of containers, inlet and discharge pipes therefor, an air pipe intercommunicating the upper end portions of the containers for equalizing pressure of air therein, detachable cages 100 engaging the upper end portions of the containers and communicating therewith, inwardly-opening valves carried by the cages for venting the containers when subjected to internal exhaustion, and sealing plates detachably fitting upon the upper ends of the containers about certain of said pipes and having portions overlapping said cages to maintain the same in position upon the containers.

In testimony whereof I affix my signature in presence of two witnesses.

JACKSON FLECKENSTEIN.

Witnesses:

J. C. TAYLOR,
J. L. FOWLE.
